United States Patent Office.

SAMUEL MEADOWS, OF TORONTO, CANADA, ASSIGNOR FOR ONE-HALF TO
THOMAS KEARTON MORGAN, OF SAME PLACE.

Letters Patent No. 96,336, dated November 2, 1869.

IMPROVEMENT IN REFLECTORS.

The Schedule referred to in these Letters Patent and making part of the same.

To all whom it may concern:

Be it known that I, SAMUEL MEADOWS, of Toronto, in the Dominion of Canada, have invented a new and improved Reflector; and I do hereby declare that the following is a full, clear, and exact description thereof, which will enable others skilled in the art to make and use the same, reference being had to the accompanying drawing, forming part of this specification.

The object of this invention is to provide a glass reflector, having the glasses so arranged as to have greater power than those now in use, and so that portions of the reflecting parts may be adjusted to throw the light on any given point; and also so arranged, in respect to the frame for the support of the glass, that the same may be easily and cheaply put together and parts removed for the substitution of other glasses when broken.

Figure 1, in the accompanying drawing, represents a top view of my improved reflector, and

Figure 2 represents a section of the same, taken on the line *z z* of fig. 1.

I make the frame *A*, which may be of any preferred form, square, pyramidal, sexagonal, octagonal, or according to the number of adjustable reflecting-glasses to be used, of cast-metal sectional plates, with flanges *a*, having recesses, and projections *b*, arranged to fit or lock together, and hold the parts in position when connected by links *C*, so that any one plate or section may be readily taken out.

These sectional plates support fixed corrugated mirror-reflector glasses *B*, and each is provided with a large circular orifice, *D*, wherein concave mirror-reflectors *E* are adjustably supported on transverse rods *F*, spanning the orifices and supported in studs *G*, projecting from the exterior faces of the plates, one of the

said studs for each glass being provided with a set-screw for holding the rods.

These reflectors *E* may thus be adjusted to throw the light from one or more burners to various points in the room, and may be placed on any or every side or section of the frame.

The corrugated fixed glasses *B* are plated in the same manner as mirrors, and covered with white enamel for protection, causing the light to be greatly refracted. These glasses are fastened in the sectional plates by plaster-of-Paris or other cement.

To further increase the power of this reflector, I suspend a reflector, *G*, similarly formed in its general features, except that the exterior surface constitutes the reflecting part, from the centre of the top, as shown by a rod, *H*, having corrugated glass reflecting-surfaces, and small concave reflectors *I*, whereby the power is greatly increased.

Having thus described my invention,

I claim as new, and desire to secure by Letters Patent—

1. The adjustable concave reflectors *E*, combined with the case *A*, having the corrugated reflectors *B*, and all arranged substantially as specified.

2. The combination, with the reflector *A*, of the inverted reflector *G*, the former being adapted to receive an adjustable reflector, as and for the purpose specified.

3. The sectional glass-supporting plates, joined together by the recessed flanges *a*, projections *b*, and links or ties *C*, all substantially as specified.

SAMUEL MEADOWS.
